UNITED STATES PATENT OFFICE.

RALPH E. NOBLE, OF CHICAGO, ILLINOIS.

COMMUTATOR.

1,077,914.

Specification of Letters Patent.

Patented Nov. 4, 1913.

Original application filed July 2, 1910, Serial No. 570,102. Divided and this application filed August 14, 1911. Serial No. 643,834.

To all whom it may concern:

Be it known that I, RALPH E. NOBLE, a citizen of the United States, residing at Chicago, in the county of Cook and State of Illinois, have invented certain new and useful Improvements in Commutators, of which the following is a specification, this application being a division of my former application, Serial No. 570,102, filed July 2, 10 1910.

This invention relates more particularly to commutators, having internal contact surfaces for the brushes, and to the method of securing such commutator to the armature of the motor; although some features thereof may be applicable to other types of commutators.

Among the objects of this invention are to provide a simple and efficient commutator having segments or bars which may be made very readily and cheaply; to provide means for securely clamping the bars or segments together so that the same may be assembled if desired before being placed in position in the motor or generator; and to provide means for securely fastening the complete commutator in position. I accomplish these objects and secure such other advantages as may appear hereinafter by means of the apparatus shown in the accompanying drawings in which:

Figure 1 is a sectional view of a motor showing my improved commutator in position, parts being broken away for convenience in illustration; Fig. 2 is a plan view of a portion of the device shown in Fig. 1; Fig. 3 is a sectional detail showing the clamping rings; Fig. 4 is a detail of one of the bars or segments; and Figs. 5 and 6 are details showing a modified form of bar or segment.

As shown in these drawings, 7 indicates an armature having a spider 8 and a rear end plate 9 which are securely bolted together to clamp the disks 10 in position. The armature is provided with windings 11, preferably of the barrel type, within the end turns of which is preferably located the commutator 12. The commutator bars or segments 13, as indicated in Figs. 1 to 4, are made of stock of uniform cross section, the sides of the bars converging so that, when the insulating strips 14 are placed between the same, they will fit together to

form an annular ring. By making these 55 bars of uniform cross section they may be cut from stock rolled in long strips for this purpose and may therefore be made very readily and cheaply. The radials 15 may be secured to the bars in any desired manner. For instance, the end of the bar may be slotted and the radials riveted therein by means of rivets 16 as clearly indicated in Fig. 4. These radials preferably extend out from the outer ends of the bars and the 60 leads from the armature coils are usually soldered thereto. The annular ring, formed by the commutator bars or segments and the intermediate insulating strips, is insulated from the adjacent parts by means 65 of an insulating band 16' and an insulating disk 17 which embrace the outer sides and inner ends of the bars. Around the band 16' is passed a clamping ring 18 which is beveled around the outer end, and is split 70 diagonally as indicated at 19 so that, when this ring is pressed inwardly, the ends of the segments thereof may slide upon each other sufficiently to allow the rings to be pressed against the band 16'. 80

The inner edges of the segments of the ring 18 are rounded or cut away adjacent to the slits 19 as indicated at 20 so that the insulating material of the ring or band 16' may be slightly pressed therein when the 85 ring is tightened. A second clamping ring 21 is beveled on its inner surface to engage with the outer beveled surface of the ring 18 and its inner end fits within a flange 22 on a supporting ring or plate 23. The inner 90 side of the ring 18 rests against this plate. Bolts 24 extend out through the plate 23 with their threaded ends engaging with tapped holes in the ring 21 so that when these bolts are tightened the ring 21 will be 95 drawn inwardly, thereby pressing against the segments of the ring 18 which will securely clamp the insulating band 16' and commutator parts 13 and 14 together to form a substantial commutator. The holding plate or ring 23 is provided with inwardly extending lugs or projections 25 which bear against the end of the spider 8, portions of the spider being preferably cut away to receive these lugs as indicated in 100 Figs. 1 and 2. The plate 23 is held in position by means of bolts 26 which extend through the spider and rear end plate 9 and

have their threaded ends engaging with tapped holes in the lugs 25. The commutator and its clamping and supporting rings are insulated from the armature windings by means of insulating material 27 placed between them. The brush or brushes indicated at 28 may be made in any desired manner, these brushes making internal contact with the commutator as shown in Figs. 10 1 and 2.

The construction and operation of my improved commutator will be readily understood, by those familiar with the art, from the above description and the accompanying drawings.

It is particularly noted that, by means of my improved construction, the commutator may be made very readily and cheaply and is of substantial construction, the arrangement being such that the commutator may be completed and may then be readily secured to the armature by means of the bolts 26 which hold it securely in position.

Instead of the form of bars and radials heretofore described, I may in some instances use the form shown in Figs. 5 and 6. As shown in these figures, the bar 29 is made integrally with the radial 30, these by being forged out of suitable material. While this construction does not permit of the bars or segments being made from strips of stock material, yet the combined segments and radials may be rapidly and economically formed by means of suitable dies.

Having thus described my invention, which, however, I do not wish to limit to the exact details of construction or arrangement of parts herein shown and described, except as set forth in the following claims,

what I claim and desire to secure by Letters Patent is:

1. In a commutator, the combination of a flanged ring, a collapsible ring engaging therewith, said collapsible ring being formed of beveled segments, a second beveled ring engaging with said collapsible ring, means for adjusting said last-named ring with respect to the flanged ring in order to press the beveled segments inwardly, and an annular ring formed of contact members and intermediate insulating members, adapted to be engaged by said collapsible ring and the parts held in position thereby, said last-named annular ring being insulated from the other ring. 50

2. The combination with a rotatable device comprising circularly arranged component parts, of a plurality of segmental pieces constituting a ring for encircling the device and having their lines of abutment inclined to the plane of the ring, and mechanical means for exerting a uniform inward pressure upon the said ring. 55

3. The combination with a rotatable device comprising circularly arranged component parts, of a plurality of tapered segmental pieces constituting a ring with a cylindrical inner surface and a conical outer surface, the lines of abutment of the segmental pieces being inclined to the plane 70 of the ring, a collar surrounding the ring and having a corresponding conical inner surface, and means for causing axial movement of the collar upon the said ring. 65

RALPH E. NOBLE.
